E. F. PELLETIER ET AL

FUSE

Filed Sept. 10, 1925

Fig. 1

UNITED STATES PATENT OFFICE.

EMMET F. PELLETIER, OF ST. JOSEPH, AND WALTER BANDLOW, OF BENTON HARBOR,
MICHIGAN.

FUSE.

Application filed September 10, 1925. Serial No. 55,529.

This invention pertains to improvements in fuses and has primarily for its object the provision of a fuse with means for visibly indicating fusing of the fusible element.

5 A further object resides in the provision of a fuse plug, or cartridge, combining means for indicating fusing of the link and permitting renewal of the fusible element.

10 A more specific object resides in the provision of a fuse of the above character, wherein upon fusing of the fusible element or link, one of the link holding elements is projected outwardly of the fuse casing, thus rendering a visible indication of the blowing 15 of the fusible link.

With the above and other objects in view, which will appear as the description proceeds, the invention resides in the novel construction, combination and arrangement of 20 parts substantially as hereinafter described and more particularly defined by the appended claims, it being understood that such changes in the precise embodiment of the herein disclosed invention may be made as 25 come within the scope of the claim.

In the accompanying drawing is illustrated one complete example of the physical embodiment of the present invention constructed according to the best mode so far devised for the practical application of the principles thereof.

In the drawings, Figure 1 is an elevational view of a cartridge type fuse constructed in accordance with the present invention, parts being broken away and in section to more clearly illustrate the structural features.

Figure 2 is a transverse sectional view taken on the line 2—2 of Figure 1.

40 Figure 3 is a detailed view of one of the link holding elements.

Figure 4 is a longitudinal sectional view through a plug type fuse embodying features of the present invention.

45 Figure 5 is a transverse section taken on the line 5—5 of Figure 4.

At the present time, where two or more fuses are employed, considerable difficulty is encountered by one not familiar with the circuits connected by the different fuses, in determining the fuse which has blown. The present invention overcomes this disadvantage and enables a person to readily determine the blown fuse due to a visible indica-

tion actuated or released when the fusible element is blown.

Referring more particularly to Figure 1 of the drawing, which illustrates the invention applied to a cartridge type fuse, the numeral 1 indicates a shell or hollow casing 60 formed of insulating material preferably of fibrous composition such as is commonly employed for insulating purposes in the electrical trade.

The shell 1 is exteriorly threaded at both 65 ends for the reception of the ferrules 2 and 3, respectively, both of said ferrules having their outer ends exteriorly threaded for the reception of caps 5 and 6, which abut the shoulders 7 provided by the reduced outer 70 ends of the ferrules 2 and 3.

Interposed between the ferrules 3 and end cap 6 is a slotted disk 8 which receives the end of a fusible link 9, and cooperating with the cap 6, serves to securely retain one end 75 of the link 9 therebetween. The opposite end of the link 9 is carried by a plunger 10 having its outer end slidably mounted in the end of the cap 5. The inner end of the plunger 10 is flattened out at 11 and bent 80 back upon itself to form a hook 11' for the reception of one end of the link 9.

In connecting the link 9 with the plunger 10, its end is inserted within the hook 11' whereupon the link is bent back upon the 85 hook to form a crimp, thus serving to detachably and securely hold said end of the link 9.

As shown in Figure 1, the plunger 10, when in its normal position, before blowing 90 of the fusible link 9, is retracted so that its outer end is approximately flush with the end of the cap 5, the plunger being held in this position by means of the link 9 secured thereto and having its opposite end retained 95 between the disk 8 and the cap 6.

For the purpose of projecting the plunger 10 upon severing or blowing of the link 9, a washer 12 is secured on the plunger, while surrounding the plunger and normally 100 housed within the ferrule 2, is an expansible coiled spring 13 abutting the washer 12 at one end, and engaging an annular flange 14 projecting inwardly from the ferrule 2 at the other end.

105 From the foregoing, it will be apparent that upon severance or blowing of the fuse 9, the plunger 10 will be released and pro-

jected outwardly of the cap 5 by means of 26 and collar 28, serves to urge the plunger in one direction. The outer end of the plunger 27 has mounted thereon an insulating sleeve 29 which has a slidable bearing in the opening 15' provided in the end of the casing 15. Surrounding the sleeve 29 and cooperating with the tapered collar 28, is a ferrule 30 adapted for wedging engagement with the collar for the purpose of retaining one end of the fusible link 22.

A detailed description and explanation of 5 the manner in which the ferrules and end caps are connected by the link and plunger to close the circuit in which the fuse is employed, is avoided in that this in no way differs from the conventional types of fuses 10 now upon the market.

Referring to that form of the invention illustrated in Figures 4 and 5 wherein the same is shown in connection with a socket or plug type fuse, the same comprises a 15 hollow casing 15, having its inner end exteriorly threaded for its insertion into the conventional type of socket while its outer end is closed and provided with an opening 15' through which the visible indicating 20 means, to be described, is projected. It will be understood that the casing 15 is formed of insulating material such as porcelain or fibrous composition, and is provided with a reduced portion which is exteriorly threaded 25 and has clamped thereon and conforming to its threads, a thin metal sleeve 15" which serves as a conductor.

Carried by the casing 15 and projecting into the open end thereof, is a unit 16 which 30 serves to carry both the fusible element and the means for visibly indicating blowing of the same.

The unit 16 comprises an end closure 17 having a reduced portion 18 projecting inwardly therefrom. Fitted over the reduced 35 portion 18 is a nipple 19 which projects inwardly of the casing 15. Surrounding the outer end of the nipple 19 is an annular ring 20 having an inwardly projecting flange 21 disposed between the end closure 17 and the 40 nipple 19 for the purpose of retaining one end of a fusible element 22. The annular ring 20, which is slightly tapered, is provided with a slot 23 for the reception of one 45 end of the link 22.

Cooperating with the ring 20 and adapted to be fitted snugly thereover is a tapered ferrule 24 provided with an outwardly projecting flange 25 adapted to engage a conductor sleeve surrounding the casing 15 and to be retained between the end of said sleeve and the end closure 17.

Cast or otherwise suitably secured within the end closure 17, which is formed of insulating material similar to the casing 15, is a plug 26 which forms one of the contact members of the fuse. The inner end of the plug 26 projects inwardly of the cap 17 and is in threaded engagement with the nipple 19, for the purpose of holding the nipple and end closure in associated position.

Slidably mounted within the plug 26 is a plunger 27 on which is secured a tapered collar 28, while a coil spring 32 surrounding 60 the plunger and engaged between the plug

26 and collar 28, serves to urge the plunger in one direction. The outer end of the plunger 27 has mounted thereon an insulating sleeve 29 which has a slidable bearing in the opening 15' provided in the end of the casing 15. Surrounding the sleeve 29 and cooperating with the tapered collar 28, is a ferrule 30 adapted for wedging engagement with the collar for the purpose of retaining one end of the fusible link 22.

From the foregoing description, it will be apparent that the unit 16 serves to carry both the visible blowing indication means and the link 22. For the purpose of permitting renewal of the link 22 and setting of 70 the indicating means, the unit 16 can be bodily removed from the casing 15 inasmuch as the same is merely inserted within the casing 15, and loosely held in proper position by means of the longitudinal webs 31 80 projecting from the nipple 19 and engaging the inner wall of the casing 15. While the unit 16 is merely inserted loosely within the casing 15, it will be readily appreciated that when the casing 15 is screwed into the conventional fuse socket, the conductor 26, secured within the end closure 17 and the nipple 19, will engage the bottom of the socket and serve to hold the unit 16 securely 90 within the casing 15.

In the operation of the plug, as illustrated in Figure 4, the parts are shown in their normal position wherein the link 22, having one end tightly secured between the ring 20 and ferrule 24, and its opposite end between the collar 28 and the ferrule 30, serves to hold the plunger in retracted position against a spring 32 and that, upon fusing of the link 22, the plunger will be released and projected by means of the spring thus allowing the insulating sleeve 29 to serve as a visible indication that the fusible element has been blown. In this connection, it will be noted that the purpose of the insulating sleeve 19 is to prevent the possibility of direct contact with the plunger when the same is projected, although when projected, the plunger 29 would, under practically all conditions, be disconnected from the circuit closed by the fuses, under some conditions, such as where a long link is used, one handling the fuse might be otherwise subject to shock were direct contact with the plunger 110 permissible.

In order to renew the fusible member and again set the indicating means, the entire unit 16 is withdrawn from the casing 15 and the ferrules 24 and 30 are removed to permit insertion of the ends of the link 22. The ferrules are then forced back into their respective positions, as shown in Figure 4, which serves to securely retain and hold the sleeve 29 in retracted position indicating that the fuse is ready for operation.

While the present invention has been

shown in two forms, it will be quite apparent that the principles of the invention are embodied in both, namely, means whereby the fusible element may be renewed and one of the link retaining members being adapted for projection from the casing to visibly indicate blowing of the fusible element.

We claim:

A fuse comprising a plug-like member 10 open at its inner end and having an aperture through its outer end, a threaded metal ferrule surrounding the inner end of said casing, a removable unit normally positioned within said casing and having a base provided with a central conductor, a movable member carried by said unit and having a

portion projecting through the aperture through said casing, a spring urging the movable member outwardly, and a fusible link removably held between said movable member and the base of said unit, said link being connected to the central conductor of said unit and to said metal ferrule, said movable member having a clamp for clamping one end of said fusible link.

In testimony that we claim the foregoing we have hereunto set our hands at St. Joseph, in the county of Berrien and State of Michigan.

EMMET F. PELLETIER.
WALTER BANDLOW.
